UNITED STATES PATENT OFFICE

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

LAUNDRY MACHINE

Application filed March 25, 1927. Serial No. 178,182.

This invention has reference to laundry machines and particularly to that type preferably used in the homes, and it has for its principal object to combine in such a machine a washing tub having a washing element, and a centrifugal extractor positioned there alongside for drying the clothes or other materials; such extractor including a revolvable housing for receiving and conducting water from said extractor and provided with a drain board or shelf adapted, by revolving said housing to position said drain board above the tub or other receptacle.

The invention has for one of its important objects to provide for a more compact assembly of the washing tub and the centrifugal extracting member within the machine frame, whereby the smallest possible space may be occupied consistent with the multiple operations performed. To accomplish this purpose the wall of the washing tub is formed or provided with a preferably concave seat in which is positioned and adapted to be revolved the centrifugal extracting member; which being thus so positioned, the distance between its axis and the axis of the washing element of the tub is considerably shortened and the washing and drying operations therefore made more convenient and easy.

A further object and an important improvement in machines of this character is to provide a floating connection between the lower end of the centrifugal extracting member and the driving element for revolving the same. Such improvement combined with a self aligning anti-friction bearing for the upper end of said member makes for an efficient centering of the said member and the consequent spinning of the same at the proper speed for producing the best centrifugal action.

The invention has for a still further object to provide an improved cover or lid for the extracting member and the supporting means therefor to permit said cover or lid to rotate with said member; said cover or lid being carried by the revolvable housing which is adapted to be manually and circumferentially adjusted around the upper end of said

member to position a drain carried thereby over a tub or other receptacle.

Other and further objects will more fully appear.

That the invention may be more fully understood, reference is had to the accompanying drawings forming part of this description, illustrating a preferred embodiment of the invention, in which:

Fig. 1 is a plan view, on a greatly reduced scale, showing a machine embodying my invention, the housing and its drain being shown by full and dotted lines in different adjusted positions;

Fig. 2 is an elevation of the machine shown in Fig. 1, parts being shown in section to illustrate the interior of the extracting member and housing therefor;

Fig. 3 is a plan, partly in section, as the same would appear if taken on the line 3—3 Fig. 2;

Fig. 4 is a vertical sectional view, with parts seen in plan in Fig. 1 transposed, and as the same would appear if taken on the line 4—4 Fig. 1, the cover for the extracting member and support therefor being shown raised in dotted lines;

Fig. 5 is a detail perspective view of one end, preferably the locking end, of the support for the cover for the extracting member;

Fig. 6 is a sectional detail, in plan, as the same would appear if taken on the line 6—6 Fig. 2, and

Fig. 7 is a detail sectional view showing parts or openings in the cover for the extracting member for the passage of water discharged by centrifugal action from said member into the housing associated therewith.

Fig. 8 is an enlarged detailed sectional view of the self aligning anti-friction bearing for the cover arranged to close the extracting receptacle.

Like characters denote corresponding parts throughout the figures.

The frame for the machine includes standards or legs 1 and 2 in which is supported and associated in working relation a tub 3 and a centrifugal extracting member 4. The under structure for these elements preferably

comprises a frame 5 on which is suitably mounted a housing 6 within which is arranged operating means, not shown, to which is operatively connected a short upstanding driving element 7, here shown in the form of a grooved shaft which protrudes a short distance only above the housing 6, see Fig. 2. The tub 3 is provided with a washing element 8, preferably an agitator member of a type well known which is arranged to have an operative connection with a shaft 9 passing up through the bottom of the tub, as shown. Said shafts 7 and 9 may be operatively connected with the source of power, not shown, whereby they may be actuated simultaneously or separately, as may be desired.

The tub 3, while shown to be square in outline, may be round, as will be understood and said tub is supported and braced at its upper end by a frame casting 10 which extends laterally therefrom and terminates in a substantially circular extension 11, through which normally extends or projects the member 4 for rotation therein. Said extension is formed or provided with an annular flanged ring 12 providing a circular opening 13 through which extends the member 4 and the peripheral face of said ring is tapered 30 inwardly and downwardly, as at 14 to present a wedge face, as shown.

The wall of the tub 3 is provided with a concave seat 15, preferably offset from a line passing transversely through the axis of the tub 3 placing the axis of the extractor 4, arranged to be seated in said seat, not only closer than is usual to the axis of the tub 4 but in close relation to an operating side of the machine, whereby the extractor is 40 positioned for convenient use by an attendant and for the more convenient transposition of clothes and other materials from the tub to the extractor and from the extractor to a rinse tub or other receptacle; thus reducing 45 considerably the working length or width of the machine. Such seat 15 as will be understood, is disposed vertically in the wall of the tub and to provide or form such a seat as will receive an inverted cone shaped member 4, the wall forming this seat is inclined 50 downwardly and outwardly from the top to the bottom of the tub, see Fig. 2.

The extracting member 4, as will be understood, is preferably a receptacle inverted 55 cone-like in shape, being closed at its bottom and open at its upper end and with its upper edge preferably turned outwardly and downwardly, as at 16, stiffening its upper edge and providing a surface engaging portion for a cover or lid, to be described. To the underside of the bottom of said member 4 and disposed axially thereof is secured a shallow engaging plate 17 formed interiorly with a seat 18 and provided with an axially 60 disposed opening 19 therethrough with its

wall splined, as at 20, see Fig. 6 to match the grooves in the driving element 7 and to have a slidable and detachable relation therewith. The plate 17 and the driving element 7 form or provide a floating connection at the lower end of the member 4 with its operating means; such connection providing a substantially free slip on and off connection for the extracting member 4 with its driving element. The upper end of said member 4 being adapted to revolve freely within the extension 11 of the frame 10 and within a housing, to be described, and to be centered and closed at its upper end, by a cover or lid, to be described, the latter including a self aligning anti-friction bearing, whereby an effective and true bearing may be provided for the rotation of said member 4.

A housing 21 is supported on the extension 11 to be manually and circumferentially adjusted on said extension and said ring 12 and about the upper end of the member 4 which is normally revolvably carried within said housing. Said housing being formed or provided with an upstanding ring 22 adapted to encircle the member 4 and to lie within or immediately under the curved upper edge of said member 4, and being also formed or provided with a depending ring 23 encircling the flanged and tapered ring 12 of the frame 10 and spaced therefrom, and between which spacing and anti-rattling blocks 24 are placed, only one of which is shown, see Fig. 2. The housing 21 is freely supported to be manually rotated into different positions, but may also be locked in different positions by a screw 25 adapted to wedge one of the blocks 24 into an impinging locking relation with the wedge face of the ring 12.

The housing 21 through its outer wall and the inner ring 22 provides a chamber 26 within said housing to receive water expelled from the member 4 due to centrifugal action when the member 4 is in rotation, and said chamber terminates in a conduit 27 formed in a radial extension 28 of said housing, through which the water is conducted and the same discharged through a downwardly directed outlet 29 and from thence into the tub 3 or other receptacle depending on the position of the housing and its radial extension 28. This extension is partitioned, as at 30, so as to provide a shelf or drain portion over which clothes and other materials are passed to and from the member 4 and to catch drippings from any such materials. The bottom of the conduit 27 with its discharge opening 29 is normally elevated or raised a sufficient distance above the tub 3 and its upper frame 10 so that an attendant's hands may not be hurt when grasping the extension 28 to swing the housing over the tub 3, or other receptacle. The upper wall of the housing 21 is provided with an enlarged opening 31, having a di-

ameter larger than the diameter of the upper turned edge 16 of the member 4, whereby said member may be placed in the frame and removed vertically therefrom without the removal of the housing 21. In the present structure no cover or lid is required for the housing.

I provide a cover or lid 32 to close the upper end of the member 4. Such cover or lid, as shown in Fig. 2 is preferably dome shaped, its outer portion being preferably provided with an under curved surface 33, see Fig. 7, conforming in contour to the curved edge 16 of the member 4 and adapted to be seated thereon, as in Figs. 2 and 7, with lips 34 depending within and engaging the inner wall of the member 4. The lower surface of the engaging portion of said lid or cover 32 is provided with a circumferential row of ports or openings 35, see particularly Fig. 7, and it is through such ports or openings that water is expelled from the member 4 into the housing 21 over the upper curved portion 16 of said member 4, to be discharged from the conduit 27 through the discharge 29. Said cover or lid 32 is preferably rotatably supported from and by a cross-head or bar 36, which in closed position extends cross-wise of the housing 21 and the opening 31 in its top wall, and said cross-head or bar is hinged at 37 to said housing, its other or free end having a sloping or tapered face 38 adapted when in locked position to be seated and lie between and engage walls or flanges 36' on the housing 21, see Fig. 1. A cam lever 39 being provided to engage such tapered face for securely locking said cross-head or bar in closed position and against the torque resulting from the operation of said member 4. Said lever being pivoted at 40 to a boss on the housing, see Fig. 1. Between the cross-head or bar 36 and the cover or lid 32 I provide, as shown in Figs. 2 and 8 a suitable self aligning anti-friction bearing. Such bearing not only permits the cover or lid 32 to revolve on its support with the member 4 with which it has an operative engagement, but also permits of a limited flexing movement to align the member 4 at its upper end concentric to its floating connection with the driving element at its lower end. A preferred construction for the self aligning anti-friction bearing includes a stem 41 connected through the lid or cover 32 having a headed portion 42 seated within an annular depressed or recessed portion 43 of said lid or cover and the journal for the lid or cover 32 on said stem comprises the inner and outer races 44 and 45 encircling the stem between the head thereof and a cover plate 46 threaded into the wall forming the depressed or recessed portion of said lid or cover. The periphery of the race 45 has parallel peripheral grooves to seat sets of balls 47 and the inner peripheral face of the race 44 is preferably concave and

struck on an arc, the axis of which is the axis of the stem 41. It will be obvious therefore, that the lid or cover and its bearing means, including the stem 41 may align itself automatically, being permitted to do so by reason of the peculiar construction of the races 44 and 45 and the manner of seating the balls, all of which it is believed will be understood by those skilled in the art.

While I have not shown a casing or what might be termed a fender for the centrifugal extracting member 4, to be carried by the frame of the machine, it is understood that such could be provided without departing from or adding anything to the spirit or scope of the invention.

What I claim is:—

1. In combination, a centrifugal extractor, a driving element comprising a short up-standing grooved operating shaft, and a substantially shallow connecting member disposed exteriorly on the lower end of said extractor and having an axially disposed splined opening for slidably and detachably connecting said member and element in operative relation.

2. In combination, a centrifugal extractor, a driving element, a free slip on and off connection between the lower end of said extractor and element, and a self aligning anti-friction bearing for the upper end of said extractor.

3. In combination, a centrifugal extractor, a driving element, a free slip on and off connection between the lower end of said extractor and element, a centering member arranged for engagement with the upper end of said extractor, and a self aligning anti-friction bearing for said centering member.

4. In combination, a centrifugal extractor, a driving element, a free slip on and off connection between the lower end of said extractor and element, a combined cover and centering member arranged for engagement with the upper end of said extractor, a support for said cover movable to operative and inoperative positions and with it said cover, and a self-aligning anti-friction bearing for said cover.

5. In combination, a centrifugal extractor, a driving element, a free slip on and off connection between the lower end of said extractor and element, a combined cover and centering member arranged for engagement with the upper end of said extractor and in association therewith providing a circumferential row of ports through which water is expelled from said extractor, a support for said cover movable to operative and inoperative positions and with it said cover, and a self-aligning anti-friction bearing for said cover.

6. In combination, a centrifugal extractor, a driving element, a free slip on and off connection between the lower end of said extractor and element, a combined cover and centering

member arranged for engagement with the upper end of said extractor, a hinged support for said cover adapted to be swung for placing said cover in closed and open positions, and a self aligning anti-friction bearing for said cover.

7. In combination, a centrifugal extractor, a driving element, a free slip on and off connection between the lower end of said extractor and element, a combined cover and centering member arranged for engagement with the upper end of said extractor and in association therewith providing a circumferential row of ports through which water is expelled from said extractor, a hinged support for said cover adapted to be swung for placing said cover in closed and open positions, and a self aligning anti-friction bearing for said cover.

8. In combination, a centrifugal extractor having its upper edge turned outwardly and downwardly to provide an upper engaging surface, a cover for said extractor having an annular engaging surface adapted when in closed position to engage the engaging surface of said extractor, a movable support for said cover, and a self aligning anti-friction bearing for said cover.

9. In combination, a centrifugal extractor having its upper edge turned outwardly and downwardly to provide an upper engaging surface, a cover for said extractor having an annular engaging surface adapted when in closed position to engage the engaging surface of said extractor and in association therewith providing a circumferential row of ports through which water is expelled from said extractor, a movable support for said cover, and a self aligning anti-friction bearing for said cover.

10. In combination, a centrifugal extractor, a driving connection for the lower end of said extractor, a housing revolvably supported at the upper end of said extractor and adapted to be manually and circumferentially adjusted about the same and provided with a discharge conduit and an overlying shelf, a combined cover and centering member adapted to be brought into engagement with the upper end of said extractor, a movable support for said cover arranged to be carried by said housing, and a self aligning anti-friction bearing for said cover.

11. In combination, a centrifugal extractor, a driving connection for the lower end of said extractor, a housing revolvably supported at the upper end of said extractor and adapted to be manually and circumferentially adjusted about the same and provided with a discharge conduit and an overlying shelf, a combined cover and centering member adapted to be brought into engagement with the upper end of said extractor and in association therewith providing a circumferential row of ports through which water is expelled

from said extractor into said housing, a movable support for said cover arranged to be carried by said housing, and a self aligning anti-friction bearing for said cover.

12. In combination, a centrifugal extractor, a driving connection for the lower end of said extractor, a housing revolvably supported at the upper end of said extractor and adapted to be manually and circumferentially adjusted about the same and provided with a discharge conduit and an overlying shelf, a combined cover and centering member adapted to be brought into engagement with the upper end of said extractor, a member hinged to said housing and adapted when in closed position to lie diametrically across the top of said housing and extractor, a self aligning anti-friction bearing for said cover in operative connection with said hinged member, and means to lock said member against the torque due to the rotation of said extractor.

13. In combination, a centrifugal extractor, a driving connection for the lower end of said extractor, a housing revolvably supported at the upper end of said extractor and adapted to be manually and circumferentially adjusted about the same and provided with a discharge conduit and an overlying shelf, a combined cover and centering member adapted to be brought into engagement with the upper end of said extractor and in association therewith providing a circumferential row of ports through which water is expelled from said extractor into said housing, a member hinged to said housing and adapted when in closed position to lie diametrically across the top of said housing and extractor, a self aligning anti-friction bearing for said cover in operative connection with said hinged member, and means to lock said member against the torque due to the rotation of said extractor.

14. In combination with a centrifugal extracting member, of a housing supported to be manually and circumferentially adjusted about the upper end of said member and having a circular opening in its upper wall for the placement and removal of said member therethrough, a cross-head hinged to said housing and adapted when in closed position to lie diametrically across the opening in said housing, means to lock said cross-head in closed position, a combined cover and centering member revolvably supported by said cross-head and adapted to engage the upper end of said extractor to close the same and having ports through which water is expelled from said extractor into said housing, and a self aligning anti-friction bearing for said cover in operative connection with said cover.

15. In combination with a centrifugal extracting member, of a housing supported to be manually and circumferentially adjusted about the upper end of said member and hav-

ing a circular opening in its upper wall for the placement and removal of said member therethrough, a cross-head hinged to said housing and adapted when in closed position to lie diametrically across the opening in said housing, the free end of said cross-head having a tapered locking surface, a pivoted locking member adapted to have a locking relation with the locking surface of said cross-head, and a cover for said extractor revolvably carried by said cross-head.

16. In combination with a centrifugal extracting member, of a housing supported to be manually and circumferentially adjusted about the upper end of said member and having a circular opening in its upper wall for the placement and removal of said member therethrough and also provided with a radial shelf portion and an underlying discharge conduit in communication with said housing, a cross-head hinged to said housing and adapted when in closed position to lie diametrically across the opening in said housing, the free end of said cross-head having a tapered locking surface, a walled seat for the free end of said cross-head when in closed position, a cam lever for engaging the locking surface of said cross-head and to cause the end of said cross-head to bear against a wall of its seat, and a cover for said extractor revolvably carried by said cross-head and in association with the extractor providing openings for the expulsion of water therethrough from said extractor into said housing.

17. A revolvable housing for a centrifugal extractor, said housing having an opening in its upper wall, a supporting cross-head hinged to said housing and adapted to lie diametrically across the opening therein, a cover plate revolvably carried by said cross-head and adapted to be normally supported within said housing, and a self aligning anti-friction bearing connecting said cover plate and said cross-head.

18. A revolvable housing for a centrifugal extractor, said housing having an opening in its upper wall, and provided with a radial shelf extension and an underlying discharge, a supporting cross-head hinged to said housing and adapted to lie diametrically across the opening therein, a cover plate revolvably carried by said cross-head and adapted to be normally supported within said housing in association with the extractor and providing a circumferential row of water conducting openings, and a self aligning anti-friction bearing connecting said cover plate and said cross-head.

60 In witness whereof, I have hereunto affixed my hand this 12th day of March, 1927.

ALPHEUS W. ALTORFER.
